Primary Examiner — Kimberly Barnes(74) *Attorney, Agent, or Firm* — William J. Clemens; Shumaker, Loop & Kendrick, LLP**CLAIM**

The ornamental design for a handrail with surface pattern, as shown and described.

DESCRIPTION

FIG. 1 is a top view of a handrail with surface pattern showing our new design; and,

FIG. 2 is a top view of a second embodiment of a handrail with surface pattern showing our new design.

The broken line surrounding the handrail surfaces depicts the boundaries of the claim and forms no part thereof. The article is flat and planar. Depth forms no part of the claimed design.
